UNITED STATES PATENT OFFICE

OWEN R. SKELTON, OF DETROIT, MICHIGAN, ASSIGNOR TO CHRYSLER CORPORATION, OF DETROIT, MICHIGAN, A CORPORATION OF DELAWARE

BRAKE SHOE

Application filed October 29, 1928. Serial No. 315,744.

This invention relates to brake shoes, and is illustrated as embodied in a brake shoe for an internal expanding brake. An object of the invention is to provide inexpensive means for forming a metal brake shoe. More specifically stated the invention consists in forming the shoe by uniting two members, preferably by casting one of the members to the other and providing a tight bond between the two united members.

These and other objects and features of the invention will more fully appear from the following description taken in connection with the accompanying drawing in which:

Fig. 1 is a vertical section through a brake, just inside the wheel, showing the shoe in side elevation and the operating mechanism for the brake in section.

Fig. 2 is a side view of the shoe, parts being broken away and in section.

Fig. 3 is a view of the shoe at right angles to Fig. 2.

Fig. 4 is a sectional view taken on line 4—4 of Fig. 2.

Fig. 5 is a sectional view taken on line 5—5 of Fig. 2.

Fig. 6 is a perspective of a portion of the shoe, parts being broken away and in section.

In the form of my invention selected for illustration, a brake including a drum 10, anchor plate 12 and operating mechanism 14 are conventionally shown. A pair of brake shoes 16 are pivoted as at 18 to the anchor plate 12 and are operated by the operating mechanism 14 which consists of a pair of oppositely movable cylinders 20 forced apart by a liquid pressure.

Various methods have been employed to construct a generally T shaped shoe having a cylindrical flange and a radial web which stiffens the cylindrical flange. The shoes illustrated each comprise a flat plate, preferably a stamping. The plate is curved in side elevation to conform generally to the contour of the brake drum.

According to the present invention, a cylindrical flange 22 preferably of aluminum, is moulded to the outer edge of the plate 16, the two members forming a T shaped rigid

shoe construction to which the friction material may be applied. The outer edge of the plate 16 is irregular to form a better bond between the two members 16 and 20. In the form illustrated dovetail projections 24 are embedded in the flange 22. At the center of each dovetail a pin 26 has been provided extending through openings 28. These pins are embedded in the moulded flange 22 to more securely hold the parts together. Openings 30 in the flange 22 and at the opposite sides of the plate 16 receive the rivets which secure the friction material 32 to the flange. A portion of the flange 22 adjacent the openings 30 is depressed as shown at 31 to receive the heads of the rivets 34.

It will be understood that by such a construction a rigid shoe has been provided which is light in weight and inexpensive to manufacture. While one embodiment of my invention has been illustrated and described in detail, it will be obvious that various changes including the size and arrangement of parts may be made without departing from the spirit of my invention and it is not my intention to limit its scope other than by the terms of the appended claims.

What I claim is:

1. A brake shoe having a generally cylindrical part and a flat radial web provided with lateral pin like projections; said cylindrical part being moulded to the outer edge of said radial flange and embracing said lateral projections.

2. A brake shoe having a plate one edge of which is curved to fit the inner periphery of a brake drum, projections on one edge of said plate, pins extending through said projections, and a cylindrical flange moulded to the edge having the projections and pins, said projections and pins embedded in said flange.

OWEN R. SKELTON.
